UNITED STATES PATENT OFFICE

ARCHIE R. MIKOTA, OF MINNEAPOLIS, MINNESOTA, ASSIGNOR OF ONE-HALF TO
MAE V. LANDIS, OF ST. PAUL, MINNESOTA

GARMENT HANGER

Application filed April 7, 1930. Serial No. 442,120.

My invention relates to garment hangers and more particularly to such a hanger for either a sleeve or sleeveless garment or both.

It is well known that stores, shops and the like handling a large stock of gowns, dresses, coats, slips and other sleeve or sleeveless garments have help that do nothing else but pick up such garments that accidentally slip from their hangers while being handled, 5 brushed against, when removing adjacent garments or while removing their hangers from racks or replacing the same.

The object of this invention is to provide an extremely simple and highly efficient hanger that will positively hold a sleeve or sleeveless garment or both irrespective of the size 15 of the neck opening and prevent the same from accidentally slipping off from the holder and at the same time center the garment 20 on its hanger and support the same, as to form, the entire distance from the neck opening to the arm openings so that the garment hangs symmetrical from the hanger, thus materially adding to the appearance thereof.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is an elevation of the improved hanger; and

Figs. 2, 3 and 4 are views corresponding to Fig. 1, but on a reduced scale, showing the different ways of supporting garments therefrom.

The improved garment hanger, as shown, 40 with the exception of its suspending hook 5, is formed from a single stiff metal rod or piece of heavy wire and comprises a bow-shaped main supporting member 6 and a pair of secondary supporting members 7 on the ends of 45 said main member. These secondary supporting members 7 overlie the main supporting members 6, are vertically spaced thereabove in the same plane and substantially concentric therewith. The short transverse 50 portions of the rod between the main and

secondary supporting members afford positive stops 8 for holding a sleeveless garment X on the secondary supporting member 7, as shown in Fig. 3.

The inner ends of the secondary supporting member 7 are spaced from each other a distance corresponding substantially to the size of the neck opening in a garment and are shaped to form upstanding stops 9 for positively holding the sleeveless garment X 60 on the secondary supporting members 7, as shown in Fig. 3, or a sleeve garment Y, as shown in Fig. 4. The hook 5 is for suspending the improved hanger from a rack or other overhead support.

The curvatures of the main and secondary supporting members are such as to substantially correspond to the form of a garment to support the same the entire distance from its neck opening to its arm openings so that 70 it will hang, to form, from either the main or secondary supporting members.

It is evident that a coat-like garment may be supported on the secondary supporting members 7 over a garment supported on the 75 main supporting member 6, as shown in Fig. 3.

What I claim is:

1. A garment hanger comprising a main bow-shaped supporting member having at 80 its crown suspending means and on its ends a pair of inturned secondary supporting members which overlie the main supporting member, are vertically spaced therefrom and substantially concentric therewith, said secondary supporting members having on their inner ends raised stops spaced materially from said suspending means to permit a sleeveless garment to be placed on the main supporting member under the secondary supporting members and held by the transverse portions of the hanger between its main and secondary members from sliding therefrom, said stop being arranged to prevent a garment on the secondary members from sliding 90 thereon toward the suspending means.

2. A garment hanger formed from a single stiff rod and comprising a bow-shaped main supporting member having at its crown suspending means and on its ends a pair of in- 100

turned secondary supporting members which overlie the main supporting member, are vertically spaced therefrom and substantially concentric therewith, the inner end portions of the secondary supporting members being shaped to form upstanding stops spaced materially from said suspending means to permit a sleeveless garment to be placed on the main supporting member under the secondary supporting members and held by the transverse portions of the hanger between its main and secondary members from sliding therefrom, said stop being arranged to prevent a garment on the secondary members from sliding thereon toward the suspending means.

In testimony whereof I affix my signature.
ARCHIE R. MIKOTA.
